T. W. J. Foster
his attorney.

UNITED STATES PATENT OFFICE.

MAX MAENNLEIN, OF VIENNA, AUSTRIA.

METALLIC PLAYING CARD.

Application filed September 12, 1927, Serial No. 219,131, and in Austria April 26, 1927.

Playing cards made in known manner from metal and particularly from sheet aluminium are more resistant (durable) than cards made from card board. They 5 can be cleaned more easily and are also to be preferred in hygienic respect, as they can be subjected to disinfection without any risk of deterioration. But these advantages are opposed by the essential drawback, that 10 metal plate cards, when falling on the table, produce a metallic sound (clashing), and this is the reason why they had hitherto not been used.

The present invention aims at doing away 15 with this drawback. For this purpose experiments have been made with plates of different metals and alloys and of varying thickness. Thereby it has been found that the nature of the metal is of less importance 20 for the generation of the clashing noise than the weight of the card, as only cards of a sufficiently low weight are, when thrown on the table, influenced by the air resistance in such manner, that the card will fall flatly as 25 is the case with paper cards. During this flat falling on the table plate the air evidently performs a braking action and checks the movement of the card to such extent, that the card does not rebound, whereby the cause 30 of the generation of the disagreeable noise is removed.

The best results have been obtained with metal plates which in the usual sizes of playing cards are of about the same weight as 35 ordinary paper cards. Aluminium plate for this reason would not be entirely suitable, as an aluminium plate of the necessary small thickness to give the desired weight, would not be of sufficient stiffness, or have sufficient 40 resistance to bending strains. Further experiments had therefore been necessary to find out a material, which for the thickness determined by the above indicated conditions has a sufficient resistance to bending strain, 45 but on the other hand is at the said condition not so thin that the edges of the card will become cutting. As a material most suitable for this purpose an aluminium alloy has been found, which is known on the 50 market as duraluminium and which is approximately composed as follows: 0.5% magnesium, 3.5 to 5.5% copper, 0.5 to 0.8% manganese and the rest aluminium. A sheet 55 of duraluminium having the size of the usual playing cards and a weight of 0.3 to 0.4

grammes, that is the weight of the usual playing cards, has a thickness of about 0.3 millimeters, that is to say it is somewhat thinner than the paper cards, but it possesses sufficient elasticity to prevent bending during or by the use of the cards. Any other aluminium alloy, which has about the same specific weight and the same stiffness as duraluminium may advantageously be employed.

In spite of their smaller thickness metal sheet cards cannot be shuffled as easily as paper cards. But this drawback can be avoided by making the edges of the metal cards rounded.

In the accompanying drawing Fig. 1 is a side-view of a card on an enlarged scale, Fig. 2 a cross-section on a greatly enlarged scale of one shape of the rounded edge, marked *a* and Fig. 3 a cross-section of another shape thereof, marked *b*, both of which shapes have given satisfactory results in practice.

It may be mentioned, that paper cards had been known, the edge of which is tapered for the purpose of facilitating the shuffling and this intended result is in fact very well attained as long as the cards are new. But in practical use the sharp, but soft edges of such paper cards are very soon deteriorated so as to show many indents and on the other hand little extensions protruding sideways in the direction of the thickness of the card, so that, inasmuch as the handling of such cards and the necessity of the absence of any characteristic, laterally visible marks thereon is concerned, their state is much worse than if the edges had not been tapered.

The printing of the metal sheets is effected according to the usual methods of metal sheet printing.

Where reference is made herein to the size of the cards (either paper playing cards or metal playing cards) the size of the front of the card is referred to, and not the cubic content or thickness.

What I claim is:

A playing card comprising a thin body of flexible and springy light aluminium alloy having rounded edges, and having such a weight that it has substantially no rebound when falling flat upon a flat surface.

In testimony whereof I have affixed my signature.

MAX MAENNLEIN.
